SAFETY CAP

Dario DalPiaz, % Euroamerican Safety Center,
Via Boffalora 71/A, Milan, Italy 20143

Filed Sept. 16, 1968, Ser. No. 13,549

Term of patent 14 years

Int. Cl. D2—03

U.S. Cl. D2—231

FIG. 1

FIG. 2

FIG. 3

FIG. 4

FIG. 5

FIG. 6

FIG. 1 is a front oblique perspective view of a safety cap, showing my new design;

FIG. 2 is a side elevational view thereof;

FIG. 3 is a front elevational view thereof;

FIG. 4 is a rear elevational view thereof;

FIG. 5 is a top plan view thereof;

FIG. 6 is a bottom plan view.

The essential features of my design are shown in full lines.

I claim:

The ornamental design for a safety cap, substantially as shown and described.
